UNITED STATES PATENT OFFICE.

MARIO DEMARCHI, OF BIELLA, ITALY.

SHIELD FOR USE IN THE PRODUCTION OF RADIOSCOPES OR RADIOPHOTOGRAPHS.

Application filed January 12, 1926, Serial No. 80,826, and in Italy January 17, 1925.

My invention has for its object an apparatus adapted to avoid the diffusion of secondary rays and their dangerous effects on radiographic plates, and some drawbacks 5 in connection therewith, as will appear.

Several devices have previously been proposed to filter the radiations emanating from the anti-cathode, and to allow the direct or primary radiations only to reach the plate.

10 Generally such filters comprise sheet metal members or laminae fixed to a frame with their faces radial in respect of the source of radiations, and at a comparatively short distance from each other so as to intercept

15 the secondary radiations, which are oblique to the radial direction above referred to. The shields of this kind heretofore known perform either a translatory motion or a rotatory motion about an axis at right angles

20 to the shield. In either case the following disadvantages are observed: (1), a series of lines or a reticulation formed by the shadows of the single fixed elements (laminae) projected over the plate, and (2), a considerable 25 difference of intensity between the radiations reaching the periphery of the plate and those reaching the central zone thereof, where the motion is comparatively slow and the plate is nearer to the source of radiations.

30 According to my invention I eliminate the drawbacks above mentioned, by providing one or more series of vibratory laminae or blades of X-ray opaque material arranged 35 in a rotatable circular frame, parallel to one or more diameters thereof, each blade being fixed at one end to the frame and free to oscillate at its opposite end, the free ends substantially lying on a diameter of the 40 frame at right angles to the common direction of the blades.

In the annexed drawing there is diagrammatically shown an embodiment of my invention, Fig. 1 being a plan, while Fig. 2 45 is a cross sectional view, Fig. 3 is a partial sectional view on the line III—III Fig. 1, and Fig. 4 is a partial sectional view on the line IV—IV. Figs. 5 and 6 are side views 50 by way of example of the end portions of two pairs of contiguous blades.

55 Figure 7 is a plan view of an alternative embodiment of my invention, and

Figure 8 is a cross section of the same on line VIII—VIII.

55 The apparatus according to my invention comprises a circular frame which I assume

to be horizontal, for explicative purposes only, though practically it may take any position desired. The frame consists of a pair of superposed rings 2, 3, secured together and having suitably fixed thereto a number of blades or laminae 4 parallel to a diameter thereof. As shown by Figs. 1, 5 and 6, each of the blades 4 comprises two halves, 4^a and 4^b, respectively fixed at their outer ends to the frame and free for vibrating at their inner ends, which preferably overlap each other alternatively, from right to left, and vice-versa. The blades are contained in planes passing, as usual, through 70 the source of radiations.

By causing the frame to rotate about its centre by any means (say, for example, by means of a toothed pinion meshing with a rack on the periphery of the frame), the 75 blades will vibrate as diagrammatically shown by the dotted lines f₁, f₇ and f₁₀, in Fig. 1. As the blades are thin, attached at one end only, and are disposed edgewise to the plane of the frame, the rotation of the 80 frame will cause a vibration of the blades. A shadow effect will thus be observed on the plate, say a sequence of instantaneous 85 interruptions of the radiations reaching the plate, said sequence being in every point inversely proportional to the speed of the point of the shield, and at the same time each blade is prevented from imprinting any constant 90 shadows on the plate, so that the formation of circles or any other geometrical figure from 95 the successive shadows of the blades will be avoided, the shadows due to one half of the blades being practically eliminated by those due to the other half thereof.

My invention also provides a particular means for securing the blades to the frame.

Each blade (see Figs. 3 and 4) is provided with a pivot or gudgeon 5, engaging a V-shaped groove 6 in the lower ring 3. Opposite each groove the ring 2 has a pressure 100 screw 7, adapted to lock the gudgeon 5. This arrangement allows of an easy adjustment 105 of the transverse inclination of the blades, and has the advantage that such inclination may be varied at will, according to the distance of the source of radiations from the shield.

For the sake of simplicity the embodiment 110 of apparatus described and illustrated in the annexed drawing comprises a series of vibratory blades only, but it is obvious that a more effective interception of the secondary

radiations will be obtained by arranging over each other in a circular frame two series of blades, having respectively their longer sides parallel to a pair of diameters at right angles to each other.

Figures 7 and 8 diagrammatically show, for the sake of example, such a modified construction of a double Röntgen-rays shield. 8 is an upper circular frame provided with 10 blades divided in two halves 4^a and 4^b. 9 is a lower circular frame provided with like 15 blades 4^c and 4^d, the two frames being so arranged over each other that the longer parallel sides of the upper series of blades will be at right angles to the like sides of the lower series of blades.

My invention is not obviously limited to any particular shape of frame, nor to any particular means for imparting the rotatory motion thereto, and may be performed with 20 considerable changes in construction as compared with the embodiment shown for explanatory purposes only.

What I claim as my invention is:

- 23 1. A shield for use in the production of radiosopes or radiographs, comprising a circular frame, strip-shaped blades of X-ray opaque material mounted in said frame with their longer sides parallel to one diameter thereof, each blade being formed in two halves, and each half being fixed at one end to the frame, and being free to vibrate at the opposite end upon a motion being imparted to the frame.
- 30 2. A shield for use in the production of radiosopes or radiographs, comprising a rotatable circular frame, a number of strip-shaped blades of X-ray opaque material each substantially divided in two halves, each half 35 blade being fixed at one end to the frame and

being free to vibrate at the opposite end, and means to impart rotation to the frame.

3. A shield for use in the production of radiosopes or radiographs, comprising a circular frame, a number of blades of X-ray 45 opaque material parallel to a diameter thereof, means for adjustably securing one end of each blade to said frame, and means to impart rotation thereto, said blades being free to vibrate at their opposite ends and terminating short of each other substantially upon a diameter at right angles to the first named diameter of the frame.

4. In shields of the kind described a circular frame, a series of blades of X-ray 55 opaque material parallel to a diameter thereof, and means for securing the blades to the frame, comprising an upper and a lower superposed ring, V-shaped grooves in the upper 60 face of the lower ring, said grooves being parallel to a diameter of the frame, a gudgeon provided at one end of each blade and adapted to engage the said V-shaped grooves, and pressure screws passing through the upper ring and adapted to lock each of said 65 gudgeons in the corresponding groove in the lower ring.

5. A shield for use in the production of radiosopes or radiographs, comprising a circular frame, a series of blades of X-ray 70 opaque material arranged parallel to one diameter thereof and adapted to vibrate at one end, and a second series of blades also adapted to vibrate, arranged underneath the 75 said first named series and parallel to another diameter of the frame at right angles to the said first named diameter.

In witness whereof, I have hereunto signed my name.

MARIO DEMARCHI.
